BEAUTY MASK

Ronald Giuliano, South Orange, N. J.

Application December 5, 1933, Serial No. 701,029

1 Claim. (Cl. 128—164)

This invention relates to devices intended to be worn on the head for the general purpose of supporting the muscles of the face and neck and preventing sagging of said muscles.

The general object of my invention is to provide a hood or mask of this general character which functions as a facial cream applicator, a hair wave protector and a chin and neck supporter combined, thus providing means for keeping the hair tidy, supporting the face, chin and neck muscles in position while at the same time permitting the applications of creams or lotions to the face.

A further object is to provide a device of this character which may be easily put in place, is self-adjusting, very readily removed and thoroughly sanitary.

Another object is to provide a device of this character which will adjust itself to the face, neck and head contours of the wearer and which is particularly so designed as to draw the cheek muscles inward, thus smoothing out the wrinkles in the cheeks and under the eyes and which also acts to reduce double chins.

Other objects will appear in the course of the following description.

My invention is illustrated in the accompanying drawing, wherein:—

Figures 1, 2 and 3 are plan views of the sections forming the cap or head piece;

Figure 4 is a plan view of the chin band;

Figure 5 is a perspective view of the neck band and

Figure 6 is a perspective view showing the complete hood or mask in use.

Referring to this drawing, it will be seen that my hood or mask comprises a head portion which fits over the head and extends from the forehead just above the eyes downward nearly to the nape of the neck, a chin supporting portion which extends downward from the middle of the hood and extends beneath the chin, a neck portion which is disposed below the chin supporting portion and extends around the front of the neck nearly to the nape of the neck and at the nape of the neck is provided with ribbons adapted to extend around the neck and hold the neck portion firmly against the neck.

The hood is preferably made of three parts, a front section 10, which as shown in Figure 6 is generally speaking semi-circular in contour; a middle portion 11, which I will term the "head band" which has convexly curved side edges, and which extends over the crown of the head and is sewed to the front portion 10; and a back

portion 12 which fits over the back of the head and which is, generally speaking, nearly semi-circular. These three portions 10, 11 and 12 are stitched successively to each other as at 13. These three portions 10, 11 and 12 are made of elastic net which is known on the market as "Lastex" and the free margins of these three sections are formed with any desired ornamental border or finish.

The lower edge of the rear portion 12 is provided with a binding enclosing an elastic 14. The fine net forming the sections 10, 11 and 12 is elastic in two directions. Thus this hood portion consisting of the sections 10, 11 and 12, may be stretched to permit the hood to be applied over the head and will then contract closely around the contours of the head.

Attached to the ends of the middle portion 11 is the chin band 15 which is of satin, the upper and lower edges of the chin band being curved as shown in Figure 4, the ends of the chin band being stitched to the ends of the middle section 11 along the line 16. Disposed below the chin band 15 is the neck band 17. This is also formed of satin. The upper edge of this neck band is 25 concavely curved at 18 to fit the lower or rear edge of the chin band and its stitched thereto at 19. The ends of the neck band are concavely cut away as at 20 so as to leave tabs 21 at the lower corners to which ribbons 22 are attached. 30

It will be seen that this hood or mask is constructed of five pieces with tie ribbons 22 and that the head or crown portion is constructed of three sections, anterior, middle and posterior, reading from left to right in Figure 6, the anterior section covering the forehead. It is to be particularly noted that these sections extend entirely across the head so that there is no medial seam extending from the forehead to the lower edge of the posterior section. The chin band, it 40 will be seen, is attached to the mid-section of the hood and disposed immediately beneath the temple, the anterior peripheral edge of the chin band running downward and forward under the lower lip or slightly above the projection of the 45 chin. The neck band 17 is in one piece and is attached to the posterior peripheral edge of the chin band and to the posterior edge of the mid-section 11. The free ends of the neck band cross at the back of the neck so that practically the 50 entire neck from front to back is covered. The ribbons 22 cross in the back of the neck and are drawn forward and tie in front of the neck, thus eliminating any knots at the back of the head which would cause discomfort while sleeping.

The fabric which forms the chin band and the neck band is elastic in the direction of the greatest length. This elasticity acts to yieldingly draw the material of the chin band and neck band up 5 snugly against the outer surface of the chin, neck and cheeks so that the flesh is held firmly in place and has a constant tendency to reduce any sagging muscles, and there is also a constant tendency to pull the flesh or skin at the cheeks 10 and under the eyes rearward, thus counteracting any wrinkles beneath the eyes and any downward sagging of the cheeks but acting to draw the muscles into their natural position.

It will be seen that the neck band covers the 15 entire neck and smooths out the skin of the neck and also that the ears are held tightly pressed inward, thus counteracting any tendency of the ears to project unduly. The cap portion of my device acts as a hair protector, keeping the coif 20 fure neat over night and this is particularly necessary after the hair has been dressed. This hood or mask also protects the pillows and bed clothes from becoming soiled with beauty cream.

As an applicator, this hood or mask is used in 25 conjunction with the necessary creams and lotions, which aid in correcting flabbiness, toning up the muscles and feeding the skin with desired creams and lotions, thus building up the tissues and creating a youthful appearance.

As before stated, the chin band and the neck 30 band are elastic each in the direction of its length. The head band, however, which is the portion 11, has a two-way pull, that is, it stretches in two directions, this being necessary in order that the hood may be slipped over the head. Once on the 35 head, the hood or head portion stays placed. The chin band which is attached to the head band had a one directional pull along its length so that the constant pressure exerted on the chin muscles and the cheek muscles by the chin band 40 will reduce the chin muscles and the cheek muscles. This also applies to the neck band 17, that is, its elasticity is in the direction of its length so that the amount of pull on the ties 22 will 45 exert a constant pressure on the chin and neck

muscles, thereby reducing these muscles. Creams, lotions, salves or any medicaments can be applied to the inner surface of the chin and neck band and then the device placed in position on the respective parts of the head. Thus this hood will serve as a medicinal applicator as well as a cream applicator.

This device may also be used for retaining the contiguous parts of fractures in place and in the healing of fractures of the mandible and maxilla.

While I have illustrated a particular construction of this hood, and illustrated this hood as being formed of five pieces, I do not wish to be limited thereto, nor to the use of "lastex" or net in the construction of the hood as the head 15 portion, the chin and the neck band might be knitted in one piece or the head portion knitted in one piece and the chin and neck band knitted in one piece and attached to the head portion below the temple.

I claim:—

A beauty mask having a cap portion formed of a forward section, a middle section and a rear section, all three sections being formed of elastic net, elastically stretchable in two directions and 25 being stitched to each other, the rear section having an elastic band disposed in its lower hem, the cap being adapted to fit down over the forehead, over the ears and extend down over the back of the head nearly to the nape of the neck, 30 a chin band attached at its ends to the opposite margins of the middle section only of the cap portion and formed of soft textile fabric elastic in the direction of its length, and a neck band having a concavely curved upper edge, the band 35 being stitched along said upper edge to the chin band and extending to the cap section and stitched thereto at its upper corner, the ends of the neck band below the cap section being free and formed to overlap around the back of the 40 neck, and ribbons attached to said lower corners, the neck band being formed of soft flexible material having elasticity in the direction of its length.

RONALD GIULIANO. 45
